SKIP HOIST

Filed Oct. 20, 1926

FIG. 3.

FIG. 2.

FIG. 1.

WITNESS:

Robert A. Mitchell.

INVENTOR

Arthur Warner
BY
Augustus B. Stoughton
ATTORNEY.

UNITED STATES PATENT OFFICE.

ARTHUR WARNER, OF HAVERFORD, PENNSYLVANIA, ASSIGNOR TO R. H. BEAUMONT COMPANY, OF PHILADELPHIA, PENNSYLVANIA, A CORPORATION OF PENNSYLVANIA.

SKIP HOIST.

Application filed October 20, 1926. Serial No. 142,812.

The present invention relates to counterweighted and balanced skip hoists, and among its objects reference may be made to the following:

5 Smaller sizes of ropes, sheaves, shafts, winding machine drums, and gearing than heretofore can be used and considerable saving effected in the cost of that machinery; the impact of an empty bucket, when lowered into the loading pit, is considerably less and the jerk upon the motor is also less; and the uplift on the winding machine foundation is considerably less, permitting of the use of lighter (smaller) foundations than at 10 present.

Other objects of the invention will appear from the following description at the end of which the invention will be claimed.

In the following description reference will 20 be made to the accompanying drawing forming part hereof and in which

Figure 1 is a side view diagrammatically illustrating a skip hoist embodying features of the invention, and

25 Figs. 2 and 3 are views in connection with which a detail illustrative description will be given.

In the drawing, more particularly Fig. 1, 1 is a winding machine. 2 is a bucket. 3 is a counterweight. The winding machine 1 is connected by a rope or cable 4 with the bucket, and by an oppositely wound rope or cable 5 with the counterweight, and these ropes or cables 4 and 5 pass over sheaves at 30 the top of the tower 6. In general, these are parts of well known structures and according to this invention there is combined with them an overhead sheave 7 and an auxiliary cable 8 passing over the overhead sheave 7 and connected with the counterweight and bucket. As shown in Fig. 1 the connection to the counterweight is made by means of an equalizing sheave 9, so that the cable 8 may be regarded as an extension 35 of the cable 5. By way of further detail description the following may be said: Referring to Fig. 2 a description will be given under the conditions that the loaded bucket is rising. It is assumed that the weight of the bucket is B, of the loaded bucket is 2B, and of the counterweight $1\frac{1}{2}B$. C is the bottom 40 of the bucket travel. The load on the rope 4 to drum 1 is $1\frac{1}{4}B$ arrived at in this way.

2B (the weight of the bucket) minus $\frac{3}{4}B$ (half the weight of the counterweight) 55 equals $1\frac{1}{4}B$. The load on the counterweight rope 5 is $\frac{3}{4}B$. This is arrived at by taking one-half of the counterweight. The load on the tower is the sum of all the rope loads. It is arrived at by adding the load on both 60 right and lefthand reaches of rope 5 which equals $1\frac{1}{2}B$. Also the load on both reaches of 8 which equals $1\frac{1}{2}B$, also the load on both reaches of the rope 4 which equals $2\frac{1}{2}B$. The combined load on the winder equals rope 65 4 ($1\frac{1}{4}B$) and rope 5 ($\frac{3}{4}B$) making the load on the winder $2B$. The unbalanced load on the winder is 4 ($1\frac{1}{4}B$) minus 5 ($\frac{3}{4}B$) so that the unbalanced load is $\frac{1}{2}B$.

When lowering the bucket (Fig. 3) the 70 results are arrived at in the manner above indicated but they differ because the load has been dumped at the top. In this case the tower load is $3\frac{1}{2}B$, the load on rope 4 is $\frac{1}{4}B$, the load on rope 5 is $\frac{3}{4}B$, the combined load 75 on winder is 4 plus 5 which equals B. The unbalanced load on the winder is 5 minus 4 which equals $\frac{1}{2}B$. The impact of the empty bucket at the bottom C of the travel is due to $\frac{1}{4}B$ which is half the unbalanced load on 80 the winder.

From these tables and by comparison with known equipment those skilled in the art will understand the philosophy of the accomplishment of the objects herein set forth. It 85 may be said that the counterweight should be of appropriate weight to provide a pull in the ropes less than the weight of the empty bucket, so that it will be overhauled automatically by the lowering of the empty 90 bucket.

It will be obvious to those skilled in the art to which the invention relates that modifications may be made in details of construction and arrangement and in matters of 95 mere form without departing from the spirit of the invention which is not limited to such matters or otherwise than the prior art and the appended claims may require.

I claim:

1. An improved skip hoist including a winding machine, a bucket, a counterweight, an equalizing sheave on the counterweight, an overhead sheave and a cable passing from the winding machine to the bucket, thence 105 to the overhead sheave, thence through the

equalizing sheave, then returning to the winding machine.

2. An improvement for skip hoists which include a winding machine and a bucket and a counterweight each having cable connection with the machine, said improvement consisting of an equalizing sheave attached

to the counterweight, an overhead sheave and an auxiliary cable passing over the overhead sheave and through the equalizing sheave and connected to the countereight cable, mentioned above, as an extension thereof and to the bucket. 10

ARTHUR WARNER.
